SPRAY CLEANER

Arthur E. Miller, Buffalo, N. Y., assignor to Viscos-Meter Corporation, Buffalo, N. Y., a corporation of New York

Application June 28, 1941, Serial No. 400,302

1 Claim. (Cl. 141—1)

This invention relates to a unitary washing machine for use in service stations and garages for the purpose of removing dirt, grease, oil, and the like from engine and other automobile parts.

One object of the invention is to provide a machine of the character generally described which is economical, rapid and highly effective in operation and which reduces fire hazard to a minimum.

A still further object is to provide for facility in introducing into the machine and in removing from the machine the parts to be subjected to the action of the cleaning fluid.

A still further object is a machine wherein provision is made for directing, at will, a high velocity stream or jet of the cleaning fluid against any areas of the parts to be cleaned which, owing to their location or the character of the adhering material, may require a more severe cleaning action than they would otherwise receive.

A still further object is to provide a machine which is simple and compact in design, trouble-proof in operation and which, when desired, may be cleaned with facility.

The invention is illustrated in the accompanying drawings in which:

Figure 1 is a longitudinal section through a machine embodying the features of the invention, the cover being shown in an open position.

Figure 2 is an end elevational view.

Figure 2a is a horizontal section taken along line 2a—2a of Figure 1.

Figure 3 is an enlarged sectional view taken along line 3—3 of Figure 2.

Figure 4 is a detail section taken along line 4—4 of Figure 3.

Figure 5 is a similar section taken along line 5—5 of Figure 2.

Figure 6 is an enlarged transverse section through the machine, the cover being shown in its closed position.

Figure 7 is an enlarged detail section taken along line 7—7 of Figure 6.

Figure 8 is a similar section taken along line 8—8 of Figure 1.

The machine, as illustrated, includes a tank 10 which is preferably mounted upon a stand 11, the rim of the tank being reinforced by angle members 12. Each of the latter is welded or otherwise secured to a side wall of the tank so that one of its flanges extends horizontally across the top edge of the said wall. The tank preferably includes a cover 13 which carries corner pieces 14 on its under side. When closed the

marginal edges of the cover seat upon the horizontal flanges of the angle members 12 while the corner pieces 14 extend into the tank and engage the side walls thereof. In its open position (Figure 2) the back edge of the cover seats upon rests 15 which are carried by the angle member 12 at the back of the tank, a chain 16 which connects the angle member 12 at the front of the tank and the front edge of the cover cooperating with the rests 15 to hold the cover in its open position and entering the tank when the cover is closed.

A header 17 which is mounted adjacent and just below the top edge of the back wall 18 of the tank carries branch pipes 19. The latter extend at right angles with respect to the header and in turn carry spray heads 20 which extend at right angles with respect to the branch pipes, the spacing and angularity of the branch pipes preferably being predetermined so that when they are substantially horizontal, as illustrated in Figure 6, the spray heads will be directed downwardly, will be located substantially midway between the front and back walls of the tank and will be substantially equally spaced with respect to one another and the end walls.

The outer end of the header is mounted in a bearing block 21 while the inner end is connected by a union 22 (Figure 7) with one branch 23 of an elbow 24, the inner end of the header being threaded to receive a sleeve 25 of the union while the end of the elbow branch 23 is threaded to receive a companion sleeve 26. A flange 27 on the end of the sleeve 25 is engaged by a flange 28 on one end of a ring 29, the opposite end of the ring being internally threaded and being screwed upon the outer externally threaded end of the sleeve 26. A packing washer 30 is preferably located between the adjacent ends of the sleeves 25 and 26, the ring 29 being tightened to cause the ends of the sleeves to engage the washer with a pressure adequate to prevent leakage at the joint thus provided and being locked to the sleeve 26 by a set-screw 31. The union 22, however, is adapted to permit angular adjustment of the header about its axis to move the branch pipes 19 either to a substantially horizontal position or to a substantially vertical position and is so adjusted that the frictional engagement between the relatively movable and stationary parts will cause the branch pipes to be supported in any position to which they may be adjusted, the two positions referred to corresponding to the normal spraying and loading positions, respectively, of the spray heads 20.

The branch 23 of the elbow 24 extends through an opening 32 (Figure 2) in an end wall 33 of the tank, a second branch 34 of the said elbow being located exteriorly of the tank and being connected through a valve 35 and a pipe 36 to the outlet side of a centrifugal pump 37. A cage 38 which is carried by an electric motor 39 provides a mounting for the pump. The motor in turn is mounted upon the end wall 33 of the tank and provides a direct drive for the pump, the armature shaft 40 (Figure 4) of the motor extending through a seal 41 carried by a face plate 42 of the cage 38 into the working chamber 43 of the pump and carrying the impeller 44 of the latter.

A pipe 45 (Figure 3) leading to the inlet side of the pump passes through an opening 46 in the end wall 33 of the tank and is connected by an elbow 47 to a vertical inlet pipe 48, the latter comprising two sections which are connected by a union 48a. A filter unit 49 is carried by the lower end of the lower section of the inlet pipe. It is immersed in a body of cleaning fluid 50 in the bottom of the tank and includes an inverted shell 51 which is supported in spaced relation with respect to the bottom of the tank and which has inner and outer screens 52 and 53, respectively, suitably secured across its open end, the screen 52 being of relatively coarse mesh and the screen 53 being of a relatively fine mesh and the two being reinforced by a Z-shaped strip 54 arranged edgewise between them and the top wall of the shell. Below the filter unit the bottom wall of the tank is formed with a drainage outlet 55 which is closed by a removable plug 56.

A false bottom for the tank is provided by perforated sheet metal sections 57 and 58 which are carried upon a rectangularly-shaped frame 59. The latter has transverse bars 59a extending between its longitudinally extending members and is provided with legs 60 and 60a which rest upon the bottom of the tank and support the false bottom above the level of the body of cleaning fluid. One end of the sheet section 58 rests upon the adjacent end of the companion section while the opposite end is cut away, as indicated at 61 in Figure 2a, to accommodate the inlet pipe 48. An angle piece 62 which is carried by the under side of the section 58 cooperates with an adjacent cross bar 59a of the frame 59 to prevent the said section from accidentally or unintentionally sliding back upon the companion section, the section 58 being removable to provide access to the filter unit which may be disconnected by unscrewing the union 48a.

Preferably there are three of the legs 60 and two of the legs 60a. The former are welded or otherwise secured to the back longitudinal member of the frame while one of the legs 60a is secured in a similar manner to each of the end frame members relatively close to but spaced from the front longitudinal frame member. This has the advantage that when it is desired to remove the frame from the tank it is only necessary to grasp the front longitudinal frame member and lift it, the space between the legs 60a and the front wall of the tank being ample to accommodate the arcs described by the lower ends of the legs as the front part of the frame is lifted and withdrawn in advance of the back part. Introduction of the frame into the tank is likewise facilitated by the construction described.

The casing of the valve 35 has a branch 63 (Figure 3) which extends through an opening 64

in the end wall 33 of the tank and is connected by an elbow 65 and a nipple 66 to a hose 67, the free end of the latter carrying a nozzle 68 which when not in use may be inserted through one of the perforations in one of the sections of the false bottom. The rotatable plug 69 (Figure 5) of the valve is formed with radial passages 70 and may be angularly adjusted by a lever 71 to one position in which the outlet side of the pump is placed in communication with the header 17 and to a second position in which the outlet side is placed in communication with the hose 67. It is preferred that the impeller 44 of the pump be formed with a substantial running clearance so that the plug 69 of the valve 35 may be moved through, or permitted to remain at, the "off" position between the two "on" positions described without the necessity of shutting off the motor to avoid injury to it or the pump. A further advantage obtained is that free passage through the pump is thus provided for the solid particles which may pass through the filter unit.

In the use of the machine the cover is opened and the spray heads are swung upwardly out of the way as illustrated in Figure 2. The part or parts to be cleaned may then be introduced into the tank without any interference from the spray heads and placed upon the false bottom. The cover may then be closed, or left open if desired, and the motor started. Assuming the control lever of the valve 35 to occupy a position at right angles, in a counter-clockwise direction, with respect to the position shown, cleaning fluid will be withdrawn from the bottom of the tank, filtered, and discharged from the spray heads upon the parts to be cleaned. If during this operation it should appear that certain areas of the said parts require a more severe action the control lever of the valve may be adjusted to connect the pump to the hose 67 and the latter may be manipulated to direct a high velocity stream or jet against such areas. In this connection it will be noted that the pump 37 is located above the level of the body of cleaning fluid in the tank hence must be primed the first time the machine is used. This may be accomplished conveniently, however, merely by tipping the tank to a suitable angle to cause the cleaning fluid to enter the pump by gravity. Thereafter priming will not be required as adequate fluid for this purpose will always remain in the working chamber. The level of the charge of priming fluid which remains in the pump after each operation will be below the level at which it is possible for it to escape past the seal 41. Hence leakage of the cleaning fluid around the motor shaft will be prevented.

The machine described has the further advantage that when the motor is cut off after each use the cleaning fluid in the piping and a substantial part of the fluid in the pump will flow rapidly in a reverse direction through the inlet pipe 48 and the filter unit to clear the screens 52 and 53 of any solid materials which may have accumulated upon them, such material settling to the bottom of the tank. Frequent cleaning of the filter element is, therefore, rendered unnecessary. It will also be apparent that the machine is economical to operate owing to the small quantity of cleaning fluid required. Moreover, the cleaning fluid being filtered prior to its delivery to the spray heads and hose is not permitted to become less effective with continued use, it being noted in this connection that as the parts to be cleaned are

not immersed in the body of cleaning fluid the latter will remain more or less quiet with the result that the greater portion of the solids will settle permanently upon the bottom of the tank and will not remain in suspension. A further advantage obtained is that loss of the cleaning fluid as a result of spatter and vaporization is minimized.

I claim as my invention:

A unitary washing machine for the removal of dirt, grease, oil, and the like from engine and other automobile parts comprising a tank having a perforated false bottom in a horizontal plane upon which the parts to be cleaned are supported, the space below the false bottom constituting a reservoir for the cleaning fluid, a motor driven pump mounted externally upon a wall of the tank, and having an inlet pipe connection to said reservoir and an outlet pipe connection terminating externally of the tank, two pipe connections extending through a wall of the tank, a valve casing connected to the outlet connection of the pump and said two pipe connections, a

valve in said casing for establishing, at will, communication between the outlet connection of said pump and either of the said two pipe connections, a pipe within the tank located suitably above said false bottom and equipped with means for spraying cleaning fluid upon the parts supported upon said false bottom, a coupling between said pipe and one of said pipe connections, said coupling including a swivel joint to permit turning movement of said pipe upon its axis in order that the spraying means may be positioned for operation or placed in a non-operative position in which the parts upon which the cleaning fluid acts may be placed upon or removed from said false bottom, a flexible hose within the tank connected to the other of said two pipe connections, and a discharge nozzle carried by said hose at its free end, the discharge nozzle being available to direct a concentrated jet of cleaning fluid upon any of the parts supported upon said false bottom.

ARTHUR E. MILLER.
